UNITED STATES PATENT OFFICE

LAURA A. CHAMBERS, OF ST. LOUIS, MISSOURI

HOSPITAL EQUIPMENT

Application filed April 9, 1928. Serial No. 268,507.

My invention relates to sick bed equipment and consists in a novel bed vessel particularly adapted for use by invalids who do not have control of their bladder or bowel movements.

5 The primary object of my invention is to provide a vessel which may be placed under the invalid and may remain there for indefinite periods without discomfort such as will arise from use of ordinary bed pans.

10 Another object of my invention is to provide an article of the class described which will drain continuously or intermittently as may be desired without removing the vessel from beneath the patient.

15 Another object of my invention is to provide such an article which may be readily cleaned and, because of its construction, will not form crevices or pockets for retaining urine or other matter which tends to rot or 20 otherwise injure the rubber or other flexible material used in a device.

In the accompanying drawings which illustrate a selected embodiment of my invention—

Figure 1 is a top view of the same.

25 Figures 2 and 3 are vertical sections taken on lines 2—2 and 3—3, respectively, of Figure 1.

Figures 4 and 5 are, respectively, horizontal and vertical sections taken on lines 4—4 and 30 5—5 of Figure 2.

Figure 6 is a detail section through a portion of the drain tube showing the use of a closure for the latter.

The device includes an inflatable ring 1 35 formed preferably of rubber, each portion of which is adapted to assume a somewhat oval contour particularly when the weight of the user is superimposed thereon. A bottom member 2, also formed preferably of rubber, 40 although other flexible material may be used, is secured to the bottom of ring 1, the point of attachment being intermediate the inner and outer peripheries of the ring.

A pan member 3 of rigid material, such as 45 aluminum, enamelware, glass, or the like, is detachably mounted beneath the ring and is positioned by the bottom member 2. Pan 3 is provided with an upwardly curved return bend rim 4 which will be positioned beneath 50 the inner and outer peripheries of the ring, as

best shown in Figure 3, so that the ring will overlie the rim of the pan and the flesh of the user will always be supported at a substantial distance from the pan and cannot contact with any portion of the latter. It may be desirable 55 to seal the joint X between the edge of rim 4 and the adjacent surface of the flexible material.

The pan is provided with a depression comprising a centrally located portion 5, of substantial area, and a converging trough-like portion 6 leading from portion 5 to the drainage end 7 of the pan. This portion of the pan extends beneath the ring 1 and preferably is 60 of oval contour and of much smaller width 65 than the body of the pan. This construction provides a covered passage of rigid material from the open top portion of the pan to beyond the ring which supports the weight of 70 the user.

A nipple 8, preferably formed of glass, has a sliding fit in the discharge end 7 of the pan and is provided with a removable screen 9 at the end spaced from the pan. This end of the nipple is adapted to be received within a drainage tube 10, preferably formed of rubber, and its purpose is to enable the attendant to determine by casual inspection whether or 75 not the trough is clear for drainage purposes. The screen will prevent the passage of any 80 non-liquid matter which would have a tendency to block the drainage tube.

In Figure 6 I illustrate a closure member 11 which may be applied to the end of nipple 8 and which has a removable lug 12. This member 11 may be substituted for the drainage tube 10 when the latter is being cleaned or it is desired to use the device temporarily and 85 not for an indefinite period.

It will be seen from the above description 90 and the attached illustrations that I have provided a device well adapted for the intended purpose in that the comfort of the user is assured and a maximum degree of sanitation is provided. I am aware that bed pans with 95 rubber rings have been previously suggested and used to some extent, particularly for temporary purposes, but I know from years of hospital work that there is nothing in general use which is adapted to meet the condi-

tions stated in the beginning of the specification, that is, a device which may be used indefinitely without inconvenience to the user, without quickly becoming unusable because of its insanitary condition.

5 It will be obvious that various changes may be made in the details of the construction of my device without departing from the spirit of my invention, and I contemplate the exclusive use of such modifications as come 10 within the scope of my claims.

I claim:

1. In a device of the character described, a pan of rigid material, and an inflatable 15 ring surrounding said pan so as to rest upon the surface which also supports said pan and providing a compressible cushion overlying the edge of said pan.

2. In a device of the character described, 20 a pan of rigid material, there being a depression formed in said pan comprising a central portion of substantial area and a converging trough leading therefrom, a portion of said trough having a rigid cover, and an 25 inflatable ring overlying the edge of said pan and overlying the covered portion of said trough.

3. In a device of the character described, an inflatable ring, a pan of rigid material 30 with an upwardly curved return bend rim assembled with said ring so that said rim is positioned intermediate the inner and outer peripheries of said ring, and a bottom member of flexible material for retaining said pan 35 and having its edges secured to the bottom of said ring intermediate the inner and outer peripheries of the latter.

4. In a device of the character described, an inflatable ring, a removable pan of rigid 40 material with an upwardly curved return bend rim assembled with said ring so that said rim is positioned intermediate the inner and outer peripheries of said ring, and a bottom member of flexible material for detachably securing said pan and having its 45 edges secured to the bottom of said ring intermediate the inner and outer peripheries of the latter.

In testimony whereof I hereunto affix my 50 signature this 6th day of April, 1928.

LAURA A. CHAMBERS.
